Patented Dec. 23, 1924.

UNITED STATES PATENT OFFICE.

HENRY M. SHEER, OF QUINCY, ILLINOIS.

HEATER FOR HOVERS AND BROODERS.

Application filed January 16, 1924. Serial No. 686,636.

To all whom it may concern:

Be it known that I, HENRY M. SHEER, a citizen of the United States, residing at Quincy, in the county of Adams and State 5 of Illinois, have invented certain new and useful Improvements in Heaters for Hovers and Brooders, of which the following is a specification.

My invention relates to an improvement 10 in heaters for hovers and brooders.

The object is to prevent the floating dust and particles in the surrounding air from settling down or drifting into the air intake. The construction is such that even in a severe test such as is sometimes given in a trick demonstration, gasoline can be squirted or even poured down upon the open ends of the air intakes without danger of entering the tubes.

20 By the use of a number of air intake tubes, it gives a combined and aggregated area which will provide several times the volume of air needed by the burner, hence there will be no suction or draft in the tubes 25 to draw in dust or gasoline fumes in such a manner as to cause explosion to the outer or open ends of the intake tubes.

Furthermore, in this present construction, even the squirting or pouring of gasoline all 30 over the radiator on intake tubes will not affect the flame.

At the same time my improved burner will not create smoke and suffocating fumes, the presence of which as is well known 35 would be detrimental and destructive to the life of the young chicks.

In the accompanying drawings:

Figure 1 is a vertical section of an illustrative and chosen form of my present invention;

Figure 2 is a plan view;

Figures 3 and 4 show slight modifications; and

Figure 5 is a section through the end of 45 the tube shown in Figure 4.

A is the burner secured on the upper end of the oil delivery pipe H and which pipe H also supports the fixed chamber B.

C is a removable drum or radiator and 50 carries with it the heat spreader D at the top. When access to the burner A is desired, the drum or radiator C, together with the spreader D, are lifted off the open up-

per end of chamber B with which the drum or radiator is held preferably in frictional contact.

The space 1 between the spreader D and the top flange D' on the upper end of drum or radiator C is reduced or constricted where the products of combustion pass out 60 by crimping down the outer edge of spreader D as shown at D².

This construction and arrangement insures a larger space or area 2 directly above the burner A, thus reducing back pressure 65 against the flame.

In the plan view shown in Figure 2, one form of multiple arrangement of intake tubes E is illustrated. Obviously there 70 might be any number of these.

Figure 3 shows the outer end of the intake tube E' mitered with the air inlet from beneath just as in the construction shown in Figures 1 and 2 in which the outer ends of the intake tubes are bent downwardly.

75 Figure 4 shows a T E² at the outer end of the intake mitered similarly to the construction shown in Figure 3.

The mitered ends of the tube and T as shown in Figures 3 and 4, it is repeated, are 80 intended to serve the same purpose as the downward bent ends or elbows of the construction shown in Figures 1 and 2, that is to say, to prevent explosive matter from dropping into or lodging in or being drawn 85 in as hereinbefore explained.

I claim:

1. A heater including a chamber, a drum or radiator removably supported thereon, and having an integral outwardly extending 90 flange at the upper end thereof, and a spreader supported by the flange and separated therefrom to provide a space for the escape of the products of combustion.

2. A heater including a chamber, a radiator supported thereon, and having an integral outwardly extending flange at the upper end thereof, a spreader supported by the flange and separated therefrom to provide a space for the escape of products of combustion, and air inlet tubes leading to the chamber, the outer ends of said tubes opening downwardly to prevent any foreign matter from entering the tubes.

In testimony whereof I affix my signature.

HENRY M. SHEER.
